United States Patent Office.

CHARLES N. GILBERT, JOHN F. BARKER, AND E. N. IVES, OF SPRINGFIELD, MASSACHUSETTS, ASSIGNEES TO NEW ENGLAND PORTABLE GAS WORKS COMPANY, OF SAME PLACE.

Letters Patent No. 61,004, dated January 8, 1867.

IMPROVEMENT IN APPARATUS FOR CARBURETTING AIR.

The Schedule referred to in these Letters Patent and making part of the same.

TO ALL WHOM IT MAY CONCERN:

Be it known that we, C. N. GILBERT, J. F. BARKER, and E. N. IVES, all of Springfield, Hampden county, Commonwealth of Massachusetts, have invented certain new and useful improvements in Gas-Generating Apparatus; and we do hereby declare that the following is a full and exact description thereof, reference being had to the accompanying drawings, and to the letters of reference marked thereon.

Our invention consists in certain improvements in that class of gas-generating apparatus in which the illuminating gas is produced by the passage of currents of atmospheric air over and in contact with naphtha, or other similar hydro-carbon oils, whereby the air becomes surcharged with the volatile portions of the naphtha, or carburetted, and can then be used for illuminating or heating purposes, substantially in the same manner as is ordinary gas. Our invention consists more particularly in improvements in the apparatus for the above-named purpose, patented by John H. Irwin, and also jointly by J. H. Irwin and Isaac Simmons, which Letters Patent are numbered and dated as follows: April 11th, 1865, Nos. 47,256 and 47,257; also, October 3d, 1865, Nos. 50,250 and 50,251. Heretofore all generators which have been put up under the above patents have been so built and arranged as to endanger the building in which they were placed, from the liability of the escape of gas or naphtha, either from the generator, or from the tank or barrel from which they were supplied. As naphtha is a very volatile and permeating fluid, it becomes necessary, in order to insure safety to the building lighted, that there should be no exposure of the fluid to the atmosphere, and that the generator should be so constructed and arranged that it shall be of itself perfectly safe, and, at the same time, secure from the contact of fire without, should such occur in the building from other causes. Heretofore the generator has been supplied with naphtha introduced into the same by means of a funnel, or by pumping from a can or barrel near by, and within the building, by which process the building is endangered from the escaping gas or naphtha to such an extent as to render it impossible to obtain insurance on the property, or, if obtained, only at an advanced rate. In order that the process may be used by the public, it becomes necessary to so construct and secure the generator that all objection to its use on this point may be removed.

The object to be attained by our invention having been thus shown, we will proceed to define the same.

Our invention consists of an improved method of arranging the generator, and the pipes connected therewith, and in certain improvements in the generator itself, together with the addition of a tank-house, detached from the building to be lighted, and supplied with a tank for containing the naphtha, and a force-pump; also, in the arrangement of the pipes connecting the same with the generator; also, in an improved method of heating and ventilating the chamber in which the generator is placed. The general arrangement of our generator, tank-house, and method of filling and emptying is as follows: We enclose the generator in a fire-proof and gas-tight chamber, made of brick, or other suitable material, which is provided with a man-hole by which to enter the chamber, should it become necessary at any time to repair the generator or readjust the piping. A closet is built within the chamber, which is provided with a glass window within, and is closed without with an iron door, through which the necessary pipes for filling and venting the generator pass, which pipes are built in in the inner wall, the glass window being built in the wall; both pipes and window being cemented around so as to render them gas-tight. Proper cocks are inserted in the pipes within the closet, by means of which the generator may be filled or emptied; and into this closet a damper-rod also runs, for the purpose of regulating the temperature of the chamber, which is indicated by the thermometer hanging within. The thermometer and gauges, showing the amount of fluid in the generator, can be seen through the glass window. Outside from the building, and detached from it, we place a fire-proof tank-house, in which is placed a tank for storing the naphtha, and connected with it is a force-pump, by means of which we force the naphtha through proper pipes to the reservoir of the generator, within the fire-proof chamber before described, which, by suitable cocks, is let down to the evaporating pans below. A sufficient amount of air is admitted to the same through the air-tube, and becoming carburetted, descends by means of its specific gravity to the burners throughout the building. A steam pipe, or radiating pipe, heated with hot air, is passed through the chamber for the purpose of warming it. Attached to the generator is a series of siphons, so arranged that the contents of the generator can be immediately emptied into the tank by means of the pump at the tank-house, should a fire occur in the building, and prevent access to the generator-chamber.

Having thus described the general character of our invention, we will now proceed to describe the same, more particularly, reference being made to the drawings and to the letters and figures marked thereon, similar letters and figures denoting similar parts of our invention.

- Figure 1 represents a vertical sectional view of our generator.
 Figure 2, a sectional view, showing the arrangement of the siphon tubes.
 Figure 3, a plan view of one of the evaporating-pans.
 Figure 4, a top view of the generator.
 Figure 5, a sectional view, of one of the gauges.
 Figure 6, an interior view of the chamber enclosing the generator and connecting pipes.
 Figure 7 is a front exterior view of the same.
 Figure 8, a sectional view of one of the flanges used to secure the pipes to the generator and tank.
 Figure 9, a ventilator for ventilating the chamber.
 Figure 10, an apparatus for heating the chamber.
 Figure 11, a can, with hose attachment, for filling the generator.
 Figure 12, an interior view of the tank-house, showing tank, force-pump, and connecting pipes.

The operation of our invention is as follows:

The tank *b* is filled from the outside by means of the pipe *a*, and the depth of fluid in the tank is determined by means of the petit cocks, *c c c*. Glass gauges, or a common float, may also be used for this purpose. The gas or air in the tank is allowed to escape, when the latter is receiving liquid, either from the outside or from the generator, (as will be shown afterward,) through the tube *d*, which vent pipe also serves the purpose of allowing the air to enter when the tank is being emptied by the force-pump. There is a sheet of gauze at the enlargement, *e*, of the vent pipe, to prevent the possibility of flame entering. The naphtha is forced up into the reservoir *h*, figs. 6, and 1, of the generator, through the pipe *g*, by the force-pump *f*, and the reservoir is known to be full by the return or overflow of the fluid through the tell-tale pipe *k*, it appearing in the gauge *l* when such is the case. The pipe *m* serves as a vent for the reservoir *h*, and is always open to the outer air. In this pipe, as is within all the other pipes of the same kind communicating with the outer air, is also a piece of wire gauze, for the purpose before mentioned. By means of the gauge *n*, the depth of the fluid in the reservoir *h* can be seen. The naphtha can now be admitted into the evaporating-pans *o o o*, from the reservoir, by means of the connecting pipes *g* and *r*, having the stop-cock *p*, which pans fill successively from top to bottom, the overflow from each pan filling those beneath. The height of the liquid in each pan is regulated by the metal dam *t*, surrounding the opening *u*, through which the liquid runs, the glass gauges *v v v* indicating the presence of fluid in the pans. The air is admitted into the evaporating-pans through the pipe *w*, which runs through the reservoir *h*, and communicates with the pans below. The tube *y* is for the gas within the pans to escape through when the fluid enters and displaces it, for, being heavier than air, it will pass out this pipe rather than through the greater elevation of the air-tube *w*. A considerable depth of chamber is allowed at the bottom of the generator, at *z*, that the passage of the air may not be obstructed, connecting with which is the gauge *A*. To prevent the possible overflow of the liquid through the gas pipe *B*, the exit of the carburetted air from the generator is made through the attached metallic box, *C*, to the burners below, across which box, *C*, several sections of gauze are stretched, to prevent the possible regurgitation of flame. Attached to the generator is also a series of siphon tubes, *D D*, having their shorter arms inserted in the cups *E E E*, which are set in the bottoms of the pans so that the siphons may act perfectly in exhausting them. The longer arms, *F F F*, of the siphons extend outside of the generator, and are enclosed in the tube *G*, terminating in the pipe *H*, which connects with the force pipe *g*, as does also the pipe *I*, which is, in effect, the longer arm of the siphon of the reservoir *h*. In the tube *I* is a cock, *J*, which is closed when it is desired to empty the evaporating-pans only; at all other times it is left open. The object of the above arrangement is to procure an instant and effectual means by which to empty the generator of fluid from the tank-house, should a fire occur in the building from any cause, and the approach to the generator be inaccessible. This operation is thus effected, as follows: By means of the pump *f* in the tank-house, naphtha is forced up the pipe *g*, and instead of rising to the reservoir *h*, it fills the lower pipe, *H*, and the tube *G*, also the longer arms of the siphons, and returning through the connecting pipe *N*, and tell-tale *k*, shows itself in the gauge *l*, and passes toward the tank *b*. The cock *O*, in the tank-house, is now opened, and the naphtha is instantly withdrawn from the generator to the tank *b*, rendering the generator entirely harmless should the flames reach it. When it is desired to empty the evaporating-pans of the heavy naphtha or benzole, the cocks *J* and *M* are closed, and the cocks *p* and *s* opened, by which means the siphons *F* are filled, the gauge *P* indicating when such is the case. By then opening the cock *M*, and, in the tank-house, the cock *O*, the benzole is allowed to run off. In order to heat the generator-chamber when steam is not available, and at the same time not increase the hazard, we provide the apparatus *R*, as shown in fig. 10, which consists of an air-tight box, made of suitable metal, subdivided in such a manner that the heat may be radiated most perfectly from its surface, and provided with a pipe for receiving the heated air and one for discharging the same without the chamber. When it is not desired to economize heat, a simple coil of pipe, of suitable size, and discharging outside the chamber, as shown in fig. 6, may be used. Either apparatus may be provided with suitable dampers in the entrance and discharge pipes, and may be heated by gas taken directly from the pipe, or generated by heat from the benzole, or by other suitable means. In order to vent the chamber of gas or naphtha, should any escape from the generator or connecting pipes, we provide the vent pipe *S*, leading to the outer air. We insert, also, the damper *T*, having a connecting-rod, *U*, entering the closet *V* through a stuffing-box, by which the chamber can be aired, or the temperature reduced. In order to secure the various pipes more firmly to the generator and tank, we affix the flange *X*, as seen in fig. 8, which, being tapped, receives the thread of the pipe, making a close, firm joint. That the current of vapor may be more effectually confined to the path marked out in fig. 3,

we substitute wood instead of metal for forming the subdivisions of the pans, which is easier worked, and forms a closer joint. In case it is desired to fill the generator otherwise than by a force-pump, the can with the hose attachment, as shown in fig. 11, is used, which hose is attached permanently to the pipe Y, leading to the reservoir of the generator, and is fastened to the can by means of a metallic union, attached to the hose, and fitting upon threads upon the cock of the can. We arrange the main gas pipe so that at certain points outside the wall of the building it can be opened by means of plugs, cocks, or caps, allowing all the gas to escape in case of fire.

Now, having described our invention, what we claim as new, and desire to secure by Letters Patent, is—

1. In a gas apparatus constructed on the principle before mentioned, arranging the generator in a fire-proof and gas-tight chamber, substantially as set forth.
2. Arranging a tank for holding the fluid in a separate and detached building, and connecting the same with the generator by means of a force-pump and pipes, substantially as set forth.
3. Arranging the pipes connecting the generator with the tank and pump in such a manner that the siphons can be filled and the generator emptied from the tank-house.
4. The arrangement of the gas pipes in such a manner that the condensed vapor, together with the gas in the generator and pipes, can be withdrawn from without the building, substantially as described.
5. Heating the generator by means of the radiating box or pipe passing through the chamber outside of the generator, substantially as described.
6. The use of gauges for the purpose of indicating the presence of fluid in the generator or pipes instead of petit cocks.
7. The use of metallic flanges for the purpose of securing the pipes to the generator and tank, constructed substantially as described.
8. The improved form of generator, in which the reservoir chamber *h* is added to the evaporating-pans *o o o*, both enclosed in one case, substantially as described.
9. The attachment of the metallic box *B*, arranged substantially as and for the purpose shown.
10. The improved can for filling, with the union and hose attachment, arranged substantially as shown.
11. The arrangement of the pipes *q* and *v* with the cock *p* and cock *s*, communicating with the siphon tubes and the gauge *P* in such a manner that the siphons may be operated and fluid withdrawn from the pans by the naphtha let down from the reservoir *h*, in the manner substantially as described and shown.
12. The siphon cups *E E E*, arranged substantially in the manner and for the purpose specified.
13. We claim the general arrangement of the gas-tight chamber, with the enclosed closet having the glass front and metallic door, into which closet the various pipes enter, together with the damper-rod, arranged in such a manner that the generator can be inspected and operated without necessitating an entrance to its chamber, substantially as described.
14. The general arrangement of the air-tight chamber with pipes for venting the generator and chamber, having the damper *u* and man-hole *w*, substantially as described.
